UNITED STATES PATENT OFFICE

FREDERICK WILLIAM TWORT, OF CAMBERLEY, ENGLAND

ELECTROMAGNETIC COUPLING DEVICE OR ELECTRICAL TRANSFORMER

Application filed September 27, 1928, Serial No. 308,844, and in Great Britain October 4, 1927.

This invention relates to electro-magnetic coupling devices or electrical transformers by means of which two electrical circuits may be electro-magnetically coupled together.

5 Although the invention is particularly applicable to the coupling of two circuits tuned to very high radio frequencies, such as are employed in radio signalling upon short wave lengths, it is applicable to the coupling 10 of circuits of any frequencies, and in fact has distinct advantages in connection with operation upon longer wave lengths.

The main object of the present invention is to provide a device in which energy can be 15 transferred from one winding to another without any appreciable dissipation of energy and without any of the energy being taken by components in the electrical circuits other than the winding which it is desired to influence. The invention also aims 20 at arranging two or more windings so that at any given point desired relative oscillatory potentials may be obtained, and to enable this to be carried out without affecting the 25 coupling between two windings. The invention provides windings which exhibit extraordinary stability and low losses, while being particularly insensitive to outside disturbances such as those commonly experienced 30 due to the body capacity of the operator. The novel coils are thus extraordinarily selective and have very low self-capacity so that for any given frequency or wave length, a maximum value of inductance can be employed.

According to the present invention, a coupling device having two or more windings is arranged with one winding so placed relatively to another that each of its conductors 40 is substantially shielded from its neighbouring conductors in such a way as to prevent the alternating fields set up by the current flowing in each conductor of the shielded winding from having access to any other conductor than the corresponding conductor of the other winding with which it is coupled. The most satisfactory arrangement 45 is to wind the conductors so that those of one of the windings substantially encircle or embrace the conductors of the other

winding; for example, by enclosing the latter conductors within the former conductors, which may be formed of metal tubes. Each conductor of a secondary winding may encircle a conductor of a primary winding, although if there is a step-up or step-down effect to be obtained, naturally the number of turns in the two windings will not be the same.

It is found in practice that the complete 50 shielding of one winding by the other, turn by turn, is of most importance when operating on extremely high frequencies, that is to say, for short wave length radio reception, and, on the other hand, the feature of the balance 55 winding, that is to say with each winding arranged with half on one side and the other half on the other side of the ends of the windings and with the winding coupled with it having those of its turns associated 60 with turns of the first-mentioned winding disposed symmetrically on either side of the terminal ends of the windings, is of most importance on higher wave lengths, and in particular when working on the so-called 65 broadcast band, or more particularly, approximately between 250 metres and 600 metres. It may be mentioned that in working with the novel device on wave lengths below 50 metres, the losses are reduced to a 70 very considerable extent in comparison with those previous coupling devices and that successful high frequency amplification can be obtained to an extent which it is believed has 75 been hitherto impossible.

In order that the invention may be clearly understood and readily carried into effect, one particular form of the novel coupling device will be described with reference to the accompanying drawing, in which:—

Figure 1 is a side elevation of one example of coupling device in accordance with the invention;

Figure 2 is a plan view of Figure 1, and

Figure 3 is a section through one side of 90 the coupling device on the line V—V in Figure 2; it is on an enlarged scale and shows clearly the disposition of the primary and secondary conductors;

Figure 4 is a diagrammatic illustration of 100

the coupler for the purpose of indicating the internal connections, while

Figure 5 shows a conventional circuit arrangement illustrating how the coupling device could be employed in a two-stage high frequency amplifier for short waves.

Referring first of all to Figures 1 to 4 of the drawing, the windings of the coupler are wound on a tubular former *a* of insulating material substantially cylindrical in shape with spaced peripheral ribs *b* notched to receive the windings. The secondary winding comprises two halves *c*¹, *c*² consisting of relatively fine copper tube. The primary winding is a fine cotton-covered copper wire and it is not visible except in Figure 3 as it lies inside the tubular secondary winding, but will be described below with reference to its path and the secondary conductors through which it is threaded.

The actual disposition of the windings will be best seen in Figure 4. One end of the secondary winding is connected to a contact member *IS*. The winding then proceeds around the former, making five and a half turns constituting the upper half *c*¹. After arriving at the top turn, it proceeds by an internal conductor *d* to a further contact member *ST*¹, which is conveniently arranged so that it can be connected by a conductor to the next contact member *ST*². The contact member *ST*² is joined to the lower half *c*² of the secondary winding, which constitutes five and a half turns, finally ending at the contact member *OS*. These contact members are shown diagrammatically placed in Figure 4; their true position is indicated in Figure 2 where they are lettered correspondingly. The two remaining contact members *IP* and *OP* are the beginning and ending terminals of the primary winding. The connections of this winding are clear in Figure 4, and the actual disposition of the contact members is clearly seen in Figure 2. By the arrangement of the contact members in pairs diametrically opposite, no connection leading to damage can be made when the device is plugged into a suitable base or holder such as a hollow piece of insulating material of the same shape as the former *a* and having a number of spring contacts around its upper edge to receive the projecting terminals on the coupling member.

It will be noted that the primary winding consists of cotton-covered wire threaded through the turns of the tubular secondary windings *c*¹, *c*². It consists of two and a half turns, one and a quarter turns lying in the uppermost two turns of the secondary winding *c*¹, and the other one and a quarter turns lying in the lowermost two turns of the section *c*² of the secondary winding, while the two portions are connected together by the conductors *h*¹. The uppermost turns are seen at *h* in Figure 3.

It will therefore be noted that the actual beginning and ending terminal of the secondary winding are in the middle so to speak, that is to say, they actually come out of the former between the upper turns *c*¹ and the lower turns *c*² and are merely brought down to the contact members *IS* and *OS* by conducting wires. Similarly, the primary turns are divided into two halves which are symmetrical with regard to the centre of the secondary winding. The actual mid-point of the secondary winding is represented by the conductor *d* which joins the upper turn of the section *c*¹ to the contact member *ST*¹, the latter being connected by an external wire on the base of the device to the contact member *ST*² which is in turn connected to the lower turn of the section *c*². When a tapping is required from the mid-point of the secondary coil, it is taken from one of the contact members *ST*¹ and *ST*².

Figure 5 illustrates a simple two-stage high frequency amplifier particularly intended for short wave reception. It consists of two valves *l*¹ and *l*² the former coupled to the aerial *m* by a coupling device *n*¹ constructed in accordance with the invention, and the second valve *l*² is coupled to the first valve *l*¹ by a second coupling device *n*² constructed in accordance with the invention. In each case the mid-point of the secondary windings is connected through a high resistance *o*¹ or *o*² to the filament of the respective valve. This mid-point, of course, is in fact the conductor *d*, and the fact that this is connected to the valve filaments is found to give a very stable result, the winding being hardly sensitive at all to body capacity due to the approach of the operator's hand and so forth. The lower ends of the secondary windings are joined by neutralizing condensers *p*¹ and *p*² to the anodes of the respective valves in quite the usual fashion.

It will be realized that the invention is not limited to the use of tubular conductors for the encircling winding, as the same effect may be substantially obtained by using strip or tape and wrapping this round, folding it over, or winding it helically around the conductors of the inner winding so that the latter are substantially enclosed in the strip or tape. Again, instead of encircling some turns of the primary winding by some turns of the secondary winding, the primary winding may be made tubular and the secondary winding may have its turns located within those of the primary winding. It will be understood that the conductors of the tubular winding may be made of any suitable metal and that the conductors of the inner winding may be covered with any suitable insulating material, or alternatively that a tube of insulating material may be inserted in the tubular conductors.

The benefits of the invention can be ob-

tained in a device having more than two windings. To give an example of this, a coupler may be made according to the invention embodying a reaction coil as well as the primary and secondary windings of the coupler. The primary turns may then pass through some of the turns of the secondary winding and the turns of the reaction coil pass through other turns of the secondary winding, or again, the reaction coil may be 10 distinct from either the primary or secondary windings. Again, more than two coils may be arranged concentrically, for example the primary winding may also be hollow and may contain another winding forming part of the 15 electrical circuit so as to influence it.

Having thus described my invention what I claim as new, and desire to secure by Letters Patent is:—

- 20 1. An electro-magnetic coupling device comprising a substantially cylindrical former of insulating material, a tubular secondary winding wound helically upon said former in two halves, the terminal points of said winding being free ends of the two adjacent or central turns, and a primary winding of fewer turns than said secondary winding and disposed symmetrically within the outermost pairs of turns of said secondary winding.
- 30 2. A radio frequency coupling device comprising two windings, certain turns of one of said windings being substantially tubular and each substantially enclosing one turn of the other winding within its tubular structure, the windings having their terminal ends at which current enters and leaves disposed adjacent the longitudinal centre of each winding.
- 40 3. Electromagnetic coupling device comprising a substantially cylindrical former of insulating material, a tubular secondary winding wound helically upon said former in two halves, the terminal point of said winding being free ends of the two adjacent or central turns, and a primary winding of fewer turns than said secondary winding and disposed within at least one of the turns of said secondary winding.
- 50 4. A radio frequency coupling device comprising two windings, certain turns of one of said windings each substantially inductively shielding individual turns of the other winding, the turns of the windings being so disposed that their terminal ends at which current enters and leaves are disposed adjacent the longitudinal centre of each winding.

In witness whereof I hereunto subscribe my name this 17th day of September, A. D. 1928.

FREDERICK WILLIAM TWORT.
